UNITED STATES PATENT OFFICE.

JOSEPH A. HOEGGER, OF JERSEY CITY, NEW JERSEY.

DESIGN FOR A BRACKET.

Application filed January 23, 1926. Serial No. 16,235. Term of patent 7 years.

To all whom it may concern:

Be it known that I, JOSEPH A. HOEGGER, a citizen of the United States, and a resident of Jersey City, Hudson County, New Jersey, have invented a new, original, and ornamental Design for Brackets, of which the following is a specification, reference being had to the accompanying drawing, forming a part thereof.

Figure 1 is a front elevation of the bracket showing my design, and

Figure 2 is a side elevation thereof.

I claim:

The ornamental design for a bracket as shown.

JOSEPH A. HOEGGER.
